UNITED STATES PATENT OFFICE.

FREDERICK FOSTER, OF LONDON, ENGLAND.

MEANS FOR OPENING BOTTLES CONTAINING LIQUIDS UNDER PRESSURE.

SPECIFICATION forming part of Letters Patent No. 411,890, dated October 1, 1889.

Application filed December 4, 1888. Serial No. 292,684. (No model.)

To all whom it may concern:

Be it known that I, FREDERICK FOSTER, a subject of the Queen of Great Britain, and a resident of London, Middlesex county, England, have invented certain new and useful Improvements in Means for Opening Bottles Containing Liquids under Pressure, of which the following is a specification.

The object of this invention is to provide means for facilitating the opening of ball-stoppered bottles containing liquids under pressure. For this purpose I fit each bottle with a staple having trunnions at each extremity, which rest upon the india-rubber ring in the groove made in the bottle-mouth. This staple is thus held by its trunnions in position above the india-rubber ring, and is capable of movement from side to side of the bottle-mouth, overlapping the ball-stopper and rotating upon its trunnions for this purpose.

A projecting piece or "trigger" is attached to the staple at one end, to be operated by hand, for moving the staple, and is formed into a curved "pricker" at its opposite end. The curved pricker bears against the ball-stopper, in contact with which it moves until it reaches the india-rubber ring, between which and the ball-stopper its point is forced sufficiently to cause an escape of gas, whereby the ball-stopper readily falls into the bottle, which is thus safely and expeditiously opened.

The staple, with its trigger and pricker, is formed in one piece by stamping, and is bent into the required form, as shown in the accompanying drawings, in which—

Figure 1 shows in section the neck of a bottle closed by the ball-stopper A and fitted with the "trigger-opener" B. (Shown with the pricker C in position to be forced between the ball A and the india-rubber ring which forms the seating for the ball.) Fig. 2 shows the

trigger-opener B in position after the ball has fallen from its seating by reason of the escape of gas. Fig. 3 shows the trigger-opener removed from the bottle.

B is the trigger by which the opener is operated.

C is the pricker, which is forced between the ball-stopper and the india-rubber ring to cause the required leakage.

D is the staple overlapping the ball-stopper, and E E are the trunnions by which the trigger-opener is held in position in the bottle-mouth.

Fig. 4 is a plan of Fig. 2, and in all the figures the same reference-letter indicates the same part.

Internally-stoppered bottles such as those to which this invention is to be applied—that is to say, those which are closed by means of a ball resting against an india-rubber ring placed in a groove formed in the bottle-neck—are in general use in the United States for containing aerated waters.

Having thus described my invention, what I claim as new is—

As an improved article of manufacture, the trigger-opener hereinbefore described, and particularly illustrated by Fig. 3 of the accompanying drawings, having a curved part D to overlap the stopper and trunnions E E at its extremities to form the hinge required to operate the pricker C by means of the handle B, as and for the purposes substantially as described.

In testimony that I claim the foregoing as my invention I have signed my name, in presence of two witnesses, this 13th day of November, 1888.

FREDK. FOSTER.
